A. CRAWFORD

TRIP MECHANISM FOR KNITTING MACHINE STOP MOTIONS

Filed April 13, 1926

Patented July 24, 1928.

1,678,557

UNITED STATES PATENT OFFICE.

ALFRED CRAWFORD, OF NEW BRUNSWICK, NEW JERSEY, ASSIGNOR TO CRAWFORD MANUFACTURING COMPANY, OF NEW BRUNSWICK, NEW JERSEY, A CORPORATION OF NEW JERSEY.

TRIP MECHANISM FOR KNITTING-MACHINE STOP MOTIONS.

Application filed April 13, 1926. Serial No. 101,739.

The object of my invention is to provide a simple and efficient means for tripping the stop motion of a knitting machine when the knitting thread breaks or runs out of the thread guides thereof when the thread on the cone becomes exhausted and for absorbing the vibrations in the thread of the knitting machine, to prevent whipping and tangling of the knitting thread.

10 The advantages and construction will be disclosed in detail hereinafter reference being had to the accompanying drawing of which:

Fig. 1 is a perspective view of my improved tripping mechanism illustrated in normal running position;

Fig. 2 is a view similar to Fig. 1 illustrating the tripping mechanism in an operative or tripping position;

20 Fig. 3 is a side elevation of the tripping device in a position similar to that illustrated in Fig. 1; and

Fig. 4 is a perspective view of a detail of the invention.

25 Referring to the drawing, 1 indicates a supporting arm having a base 2 adapted to be secured to the body of a stop motion (not shown) forming no part of the present invention. The outer end of the arm 1 is provided with a downwardly extending bearing 3 in which the base 2 is journaled a trip shaft 4, which is provided at its inner end with a trip crank 5 adapted to co-operate with the said stop motion to trip it when the shaft 4 is rocked clockwise.

30 A bracket 6 extends vertically from the arm 1 in a plane coincident with one side of said arm and this bracket is provided with a horizontally extending flange 7 lying adjacent the top of the arm 1 and secured thereto by means of screws 8, 8 (Fig. 3).

40 The bracket 6 is provided with lugs 10, 11 and 12 which are adapted to receive thread eyes 13, 14 and 15 respectively of porcelain or other equally hard material adapted to resist the wearing tendencies created by the running thread α in its passage from the cone, through said eyes, to the needles of the knitting machine to which the 45 device is attached.

50 The bracket 6 is provided with a second pair of lugs 16 and 17 adapted to receive a vertically extending spindle 18 which is suitably secured to a gate element 19. The gate

element 19 is provided adjacent its lower end 55 with a pair of arms 20 and 21 which lie substantially parallel to the plane of the bracket 6 but in different planes, one with respect to the other. The bracket 6 is apertured at 22 for the accommodation of the arms 20 60 and 21.

Secured to the outer end of the trip shaft 4, adjacent the bearing 3 of the arm 1, is a weighted trip arm comprising a hub 23, secured to said shaft 4, and an upwardly extending arm 24 which lies in a plane substantially parallel to the bracket 6 and occupies a position behind the arm 21 and in front of the arm 20 of the gate element 19.

On the upper end of the arm 24 is a 70 weight member in the form of a plate 25, which is secured to the arm 24 and extends outwardly therefrom and is provided with a pair of arms 26, 26. These arms 26 lie in a plane substantially parallel to the bracket 75 6 and are bent outwardly therefrom adjacent their outer ends and then inwardly toward said bracket, the ends of said arms extending into apertures 27, 27 in the bracket 6.

80 The bending of the arms 26, 26 forms crooks 28, 28 in the arms, for the purpose of guiding the thread and preventing lashing thereof; and the ends of the arms 26, 26 extend into the apertures 27, 27 in the bracket 6 to prevent the release of the thread from the crooks 28, 28.

85 The upper end of the gate element 19 is provided with an outwardly extending resilient arm 30 which may be secured to said gate member in any suitable manner and in the present instance by means of lugs 31, 31 formed integral with the gate 19 and turned upon the one end of the resilient arm 30 and upon themselves to rigidly secure 90 the said arm to the gate element, as shown in the drawing.

95 The arm 30 lies in a plane substantially parallel to the plane of the bracket 6 and the outer end thereof occupies a position intermediate the thread eyes 13 and 14 and behind the running thread α . The said outer end is convexed from the plane of the said bracket as illustrated at 32 in order to present a rounded surface, free of all sharp 100 edges, to the said running thread.

105 As viewed from the outer end of the arm 1 the trip shaft 4 is journaled at the centre

of said arm and the trip arm 24 lies in a vertical plane adjacent the right side of the supporting arm. This arrangement throws the centre of gravity of the trip arm 5 at the right hand side of its centre of rotation.

Under normal operating conditions the thread α passes through the thread eyes 13, 14 and 15, the resilient arm lies between the 10 thread α and the face of the bracket 6. The arms 26 occupy positions outside the thread α and the arm 24 lies between the arms 20 and 21 of the gate element 19, all as clearly illustrated in Fig. 1.

15 The weight 25 is retained in position by the resilient arm 30 lying behind the thread α and in event of the failure of the thread α , the resilient arm 30 is released, permitting the gate element 19 to turn and the 20 weight 25 to move outward from the bracket 6, due to its off balance centre of gravity, the arm 24 engaging the back side of the arm 21. The arm 24 continues to move in a clockwise direction, turning the trip shaft 25 4 and the trip crank 5 until the stop motion controlled thereby is operated to stop the knitting machine.

The resilient arm 30 absorbs any vibrations set up by the machine which would 30 cause the thread to whip or lash and become tangled around the thread guides.

The bracket 6 is provided with a pair of arms 34 and 35 which extend parallel to the resilient arm 30 above and below the same to 35 protect this delicate arm from accidental injury.

It is to be understood that the preferred embodiment of my invention is shown in the drawing, this form being selected for the 40 purpose of illustration and, therefore, should not be construed as limiting the scope of my invention, the device being capable of considerable modification and only such limitations should be placed thereon as are 45 prescribed by the appended claims or as may be dictated by the prior art of record.

I claim:

1. In tripping mechanism for knitting machine stop motions, the combination of thread 50 eyes for guiding the knitting thread; a rotatable trip shaft for controlling the operation of said stop motion; a weighted arm secured to and adapted to rotate said trip shaft; and a resilient arm adapted to control the rotation of said trip shaft and to absorb the vibrations on said thread between 55 said thread eyes.

2. In tripping mechanism for knitting machine stop motions, the combination of a rotatable trip shaft; a weighted arm secured to and adapted to rotate said trip shaft; means for maintaining said trip shaft and said weighted arm in their inoperative positions; thread eyes for the knitting thread; 60 and a resilient arm on said retaining means

adapted to engage said thread intermediate said thread eyes for maintaining said retaining means in its operative position.

3. In tripping mechanism for knitting machine stop motions, the combination of a rotatable trip shaft; a weighted arm secured to said trip shaft; a gate element for retaining said weighted arm in an inoperative position; thread eyes for the knitting thread; and a resilient arm on said gate element 70 adapted to engage said knitting thread intermediate said thread eyes for maintaining said gate element in its operative position.

4. In tripping mechanism for knitting machine stop motions, the combination of a supporting arm; a trip shaft on said supporting arm; a weighted arm on said trip shaft; a bracket on said supporting arm; a gate element pivoted to said bracket and adapted to engage said weighted arm; thread eyes on 80 said bracket; a resilient arm on said gate element adapted to engage the knitting thread intermediate said thread eyes.

5. In tripping mechanism for knitting machine stop motions, the combination of a supporting arm; a trip shaft longitudinally journaled in said supporting arm; substantially at the centre thereof; a bracket secured to said supporting arm contiguous with one side thereof; a weighted arm on said trip shaft and lying in a plane adjacent said bracket; a gate element pivoted to said bracket and adapted to engage said weighted arm; thread guides on said bracket; and a resilient arm on said gate element adapted to 90 engage the knitting thread intermediate said thread guides.

6. In tripping mechanism for knitting machine stop motions, the combination of a supporting arm; a trip shaft on said supporting arm; a weighted arm on said trip shaft; a bracket on said supporting arm; thread eyes on said bracket; a gate element pivoted on said bracket; an arm on said gate element adapted to engage said weighted arm 100 at one side thereof; a second arm on said gate element, adapted to engage said weighted arm on the opposite side thereof; a resilient arm on said gate element adapted to engage the knitting thread intermediate 110 the thread eyes.

7. In tripping mechanism for knitting machine stop motions, the combination of a supporting arm; a bracket on said supporting arm; thread eyes on said bracket; a trip 120 shaft on said supporting arm; a weighted arm on said trip shaft; arms on said weighted arm; crooks in said arms aligned with said thread eyes; a gate element pivoted on said bracket and adapted to engage said weighted arm; and a resilient arm on said gate element and adapted to engage the knitting thread intermediate said thread eyes.

8. In tripping mechanism for knitting machine stop motions, the combination of a 130

- supporting arm; a trip shaft on said supporting arm; a bracket on said supporting arm; thread eyes on said bracket; a resilient arm pivoted to said bracket, adapted to engage 5 the knitting thread intermediate said thread eyes and to control the operation of said trip shaft; and arms integral with said bracket and lying at either side of said resilient arm, for the protection thereof.
- 10 9. In tripping mechanism for knitting machine stop motions, the combination of
- thread guides; a trip shaft; means intermediate the thread running in said thread guides and said trip shaft for controlling the operation thereof when said thread breaks 15 and including a resilient arm, comprising a substantially flat spring adapted to engage said thread intermediate said thread guides; and a convexed portion adjacent one end thereof adapted to present a rounded smooth 20 surface to the running thread.

ALFRED CRAWFORD.
